OIL BURNER

Ernest F. Adolfson, Hazel Park, Mich.

Application September 7, 1937, Serial No. 162,678

8 Claims. (Cl. 158—91)

This invention relates to oil burners and in particular to natural draft type oil burners.

The main object of this invention is to provide a highly efficient natural draft type oil burner particularly adapted for use in domestic heating plants and the like wherein complete combustion of fuel oil burned in the said oil burner is accomplished.

Another object of the invention is to provide a natural draft oil burner wherein heated air is supplied to slow burning fuel oil in such a manner as to create complete combustion of the said fuel oil and transfer a lazy flame into a live air jetted oil flame.

15 Another object of the invention is to provide a natural draft type oil burner having a combustion bowl adapted to effectively heat fuel oil supplied thereto to a highly volatile state prior to combustion whereby to permit flame from the 20 combustion bowl of the oil burner to carry with it incompletely combusted particles of oil ready for combustion and wherein the natural draft of the burner is transformed into an air jet which contacts the said flame from the combustion 25 bowl causing complete combustion of all particles of oil in the oil flame immediately above the said combustion bowl.

Another object of the invention is to provide a natural draft type oil burner in which fuel oil 30 fed by gravity to the combustion bowl thereof is effectively heated therein prior to combustion to a highly volatile state whereby the slow burning thereof carries from the said combustion bowl particles of incombusted oil which particles of 35 incombusted oil become completely combusted at an air jet created by natural draft and warmed by the heat of the oil burner, which air jet is directed against the slow burning flame from the combustion bowl whereupon the oil partially combusted becomes completely combusted and the 40 normal lazy flame from the combustion bowl becomes live and energetic thereabove.

Another object of the invention is to provide an inexpensive simple highly efficient oil burner 45 which has no moving parts and requires no adjustments or service.

Other objects of this invention will become apparent by reference to the following detailed description taken in connection with the accompanying drawing, in which:

Fig. 1 is a cross sectional view of an oil burner embodying the invention taken along the lines 1—1 of Fig. 2.

Fig. 2 is a top elevational view of an oil burner 55 embodying the invention having certain por-

tions thereof broken away to better show the invention.

Fig. 3 is a cross sectional view through the fire box of a domestic furnace showing the installation of a natural draft type oil burner embodying the invention therein.

Referring now to the drawing wherein like numerals refer to like and corresponding parts throughout the several views, the embodiment of the invention disclosed therein comprises, in general, an annular combustion bowl 10 having a centrally disposed hub 11 spaced from the inner periphery of the said annular combustion bowl 10 by a plurality of radially disposed webs 12 through which fuel is supplied to the said combustion bowl 10; the said combustion bowl 10, centrally disposed hub 11 and radially disposed webs 12 being preferably cast as an integral whole. The said annular combustion bowl 10 has a suitable generally disc shaped cap 13 secured thereover, the said cap 13 being provided with an annular jet ring 14 having an outer depending lip 140 of less diameter than the said combustion bowl 10 secured in spaced relationship below the outer portion of the said cap 13 as best indicated in Fig. 1.

The said annular combustion bowl 10 is composed of a vertically disposed inner rim 15, a vertically disposed outer rim 16 and a bottom 17, the outer portion of the inner bottom of which is radially dished as indicated by the numeral 170 in Fig. 1. The inner portion of the bottom of the said annular combustion bowl 10 is provided with a plurality of annular steps 18, 19 and 20 rising successively upward toward an upper annular fuel distributing step 21 sloped radially inward toward the inner rim 15 of the said annular combustion bowl 10, all as best shown in Fig. 1 of the drawing.

Fuel is supplied preferably by gravity to the fuel distributing step 21 from a suitable source through the fuel supply pipe 22 communicating with the vertically disposed bore 23 in the bottom of the central hub 11 of the said combustion bowl 10 from whence it flows through diagonally disposed bores 24 in the radially disposed webs 12 to the said upper annular fuel distributing step 21.

The centrally disposed hub 11 and the radially disposed webs 12 adjacent thereto extend above the top of the annular combustion bowl 10 a sufficient distance to support the generally disc shaped cap 13 in vertically spaced relationship to the said combustion bowl 10, the said disc shaped cap 13 being secured to the said centrally

disposed hub 11 of the annular combustion bowl 10 by means of a machine bolt 25. The annular jet ring 14 having an outer depending lip 140 is secured in spaced relationship below the outer 5 portion of the said disc shaped cap 13 by suitable machine screws 26, the said jet ring 14 being vertically spaced with respect to the said disc shaped cap 13 by spacers 27.

The said disc shaped cap 13 is provided with 10 an annular depending portion 28 radially spaced with respect to the inner periphery of the jet ring 14 and so shaped and located with respect to the inner rim 15 of the combustion bowl 10 as to cause natural draft from below the annular 15 combustion bowl 10 which rises in the central aperture 29 between the inner rim 15 of the said combustion bowl 10 and the centrally disposed hub 11 thereof to jet radially outward between the top of the jet ring 14 and the bottom 20 of the disc shaped cap 13 as indicated by the arrows 30 in Fig. 1 when fuel oil is slowly burned in the inner bottom of the combustion bowl 10. A small portion of the said air passing through the central aperture 29 of the annular 25 combustion bowl 10 passes below the outer depending lip 140 of the jet ring 14 as indicated by the dotted arrows 31 in Fig. 1.

As best illustrated in Figs. 1 and 3 the combustion bowl 10 is preferably sealed in the fire box 32 of a domestic heating furnace or the like 33 above the grate bars or other suitable support 34 therein by a suitable refractory material 35.

Fuel oil from a tank or other source is supplied by gravity to the fuel supply pipe 22 through 35 a fuel line 36 and a high level fuel supply shut off valve 37 mounted so as to shut off the fuel supply to the combustion bowl 10 when fuel therein rises to the level indicated by the dot and dash line 38 in Figs. 1 and 3 to prevent fuel 40 from overflowing the combustion bowl should fuel be supplied thereto faster than it can be burned therein, to prevent overflowing of fuel oil should combustion in the oil burner cease, 45 and to prevent the overflow of fuel oil supplied to the combustion bowl 10 before the same is ignited. It will be noted that the high level of the fuel in the combustion bowl 10 is established slightly above the fuel distributing step 21 thereof.

50 The amount of draft supplied to the oil burner is preferably regulated by such suitable means as the pivoted damper 39 of the clean out door 40 positioned in the front of the said domestic heating furnace or the like 33. The amount of fuel 55 oil fed to the oil burner and the amount of draft permitted to enter the domestic heating furnace 33 or the like into which the oil burner is installed may be regulated manually or by any known thermostatic means as may be desired.

60 When the oil burner is put into service fuel oil is placed in the radially dished bottom 170 of the annular combustion bowl 10 and is ignited whereupon the said fuel oil is permitted 65 to burn slowly with the damper door 39 substantially closed. As soon as the oil burner becomes hot, fuel oil is caused to flow through the fuel supply pipe 22 to the annular fuel distributing step 21 of the combustion bowl 10. As soon as 70 the fuel distributing step 21 is filled with fuel oil, the said fuel oil overflows therefrom down the annular steps 20, 19 and 18 whereupon the said fuel oil becomes heated to a highly volatile state from the latent heat of the combustion bowl 10. The oil slowly running down the said 75

steps 20, 19 and 18 becomes ignited from the flame of the fuel oil which is burning in the radially dished inner bottom 170 of the said combustion bowl 10. As soon as the fuel oil is burned out of the said radially dished inner bottom 170 of the combustion bowl 10 the said oil burner is hot enough to function normally whereupon the damper 39 is opened and draft is permitted to enter the bottom of the domestic heating furnace or the like 33.

10 After the oil burner is once lighted and heated as hereinbefore described the fuel oil supplied to the fuel distributing step 21 gradually runs down the steps 20, 19 and 18 and slowly burns in the combustion bowl 10 with a small amount of air 15 being supplied thereto from below the said oil burner through the central aperture 29 as indicated by the dotted arrows 31 in Fig. 1. The slow burning flame of the oil running down the annular steps 20, 19 and 18 from the annular fuel 20 distributing step 21 follows the said arrows 31 out of the combustion bowl 10 between the outer rim 16 thereof and the outer annular depending lip 140 of the jet ring 14 as illustrated in Fig. 1. The heat of the slow burning flame above the 25 outer annular portion of the combustion bowl 10 between the outer rim 16 thereof and the said outer depending lip 140 of the jet ring 14 causes the majority of the draft permitted to enter the lower portion of the domestic heating furnace or 30 the like 33 to jet radially outward and upward through the space between the cap 13 of the oil burner and the jet ring 14 as indicated by the full line arrows 30 in Fig. 1. When the said air jet touches the lazy flame from the combustion 35 bowl at the intersection of the dotted line arrows 31 and the full line arrows 30 in Fig. 1, the lazy flame of the fuel oil burning in the combustion bowl 10 is transferred into a live air jetted oil flame in which complete combustion of the 40 said fuel oil previously made highly volatile by heating in the combustion bowl as hereinbefore described takes place. The said jet of air passing through the oil burner becomes pre-heated by contact therewith prior to mixing with the lazy 45 flame from the combustion bowl 10.

Although the oil burner has been shown and described in connection with a domestic heating furnace 33 or the like, it is readily observed that the said oil burner may be used wherever an oil 50 burning heating element of the type is found to be desirable.

Although but one embodiment of the invention has been disclosed and described herein, it is to be understood that various changes including the 55 size, shape, arrangement and detail of the various parts thereof may be made without departing from the spirit of the invention and it is not my intention to limit the scope of the invention other than by the terms of the appended claims. 60

I claim:

1. An oil burner comprising, in combination, an annular combustion bowl, a disc shaped cap of less diameter than said combustion bowl positioned in spaced relationship thereover, an annular jet ring spaced below said disc shaped cap, an outer depending lip on said jet ring extending into said combustion bowl but spaced from the bottom thereof, and means for distributing fuel oil supplied to the said annular combustion 70 bowl uniformly therearound.

2. An oil burner comprising, in combination, an annular combustion bowl having the inner bottom thereof radially dished to a higher elevation toward the center thereof, a disc shaped 75

- cap of less diameter than said combustion bowl positioned in spaced relationship thereover, an annular jet ring spaced below said disc shaped cap, an outer depending lip on said jet ring extending into said combustion bowl but spaced from the bottom thereof, and means for distributing fuel oil supplied to the said annular combustion bowl uniformly therearound. 5
3. An oil burner comprising, in combination, an annular combustion bowl, a disc shaped cap of less diameter than said combustion bowl positioned in spaced relationship thereover, an annular jet ring spaced below said disc shaped cap, an outer depending lip on said jet ring extending into said combustion bowl but spaced from the bottom thereof, and an annular step in the said combustion bowl sloping radially inward toward the inner rim of the said combustion bowl wherein fuel oil supplied to the said annular combustion 10 bowl is distributed uniformly therearound.
4. An oil burner comprising, in combination, an annular combustion bowl having the inner bottom thereof radially dished to a higher elevation toward the center thereof, a disc shaped cap of less diameter than said combustion bowl positioned in spaced relationship thereover, an annular jet ring spaced below said disc shaped cap, an outer depending lip on said jet ring extending into said combustion bowl but spaced from the bottom thereof, and an annular step in the said combustion bowl sloping radially inward toward the inner rim of the said combustion bowl wherein fuel oil supplied to the said annular combustion 15 bowl is distributed uniformly therearound. 20
5. An oil burner comprising, in combination, an annular combustion bowl, a disc shaped cap of less diameter than said combustion bowl positioned in spaced relationship thereover, an annular jet ring spaced below said disc shaped cap, an outer depending lip on said jet ring extending into said combustion bowl but spaced from the bottom thereof, an annular step in the said combustion bowl sloping radially inward toward the inner rim of the said combustion bowl wherein fuel oil supplied to the said annular combustion 25 bowl is distributed uniformly therearound, the said hub and radially disposed webs 25 of the said combustion bowl having communicating bores therein through which fuel is fed to the said combustion bowl at the said fuel distributing step thereof, and a plurality of annular steps in the said combustion bowl rising successively upward from the bottom thereof toward the said fuel distributing step thereof. 30
6. An oil burner comprising, in combination, an annular combustion bowl having the inner bottom radially dished to a higher elevation toward the center thereof, a disc shaped cap of less diameter than said combustion bowl positioned in spaced relationship thereover, an annular jet ring spaced below said disc shaped cap, an outer depending lip on said jet ring extending into said combustion bowl but spaced from the bottom thereof, an annular step in the said combustion bowl sloping radially inward toward the inner rim of the said combustion bowl wherein fuel oil supplied to the said annular combustion 35 bowl is distributed uniformly therearound, and a plurality of annular steps in the said combustion bowl rising successively upward from the bottom thereof toward the said fuel distributing step thereof. 40
7. An oil burner comprising, in combination, an annular combustion bowl including a central hub supported in spaced relationship from the inner periphery of the said combustion bowl by a plurality of radially disposed webs, a disc shaped cap of less diameter than said combustion bowl supported on said hub in spaced relationship above said combustion bowl, an annular jet ring substantially the same outside diameter as the 45 said disc shaped cap suspended in spaced relationship therebelow, an outer depending lip on said jet ring extending into the said combustion bowl but spaced from the bottom thereof, an annular step in the said combustion bowl above the bottom thereof sloping radially inward and downward toward the inner rim of the said combustion bowl wherein fuel supplied to the said combustion bowl is distributed uniformly therearound, the said hub and radially disposed webs 50 of the said combustion bowl having communicating bores therein through which fuel is fed to the said combustion bowl at the said fuel distributing step thereof, and a plurality of annular steps in the said combustion bowl rising successively upward from the bottom thereof toward the said fuel distributing step thereof. 55
8. An oil burner comprising, in combination, an annular combustion bowl including a central hub supported in spaced relationship from the inner periphery of the said combustion bowl by a plurality of radially disposed webs, a disc shaped cap of less diameter than said combustion bowl supported on said hub in spaced relationship above said combustion bowl, an annular jet ring substantially the same outside diameter as the 60 said disc shaped cap suspended in spaced relationship therebelow, an outer depending lip on said jet ring extending into the same combustion bowl but spaced from the bottom thereof, the inner bottom of the said combustion bowl being radially dished to a higher elevation toward the center thereof, an annular step in the said combustion bowl above the bottom thereof sloping radially inward and downward toward the inner rim of the said combustion bowl wherein fuel supplied to the said combustion bowl is distributed uniformly therearound, the said hub and radially disposed webs of the said combustion bowl having communicating bores therein through which fuel is fed to the said combustion bowl at the said fuel distributing step thereof, and a plurality of annular steps in the said combustion bowl rising from the high point of the radially dished bottom thereof successively upward from the said dished bottom thereof toward the said fuel distributing step thereof. 65

ERNEST F. ADOLFSON.
